RAILWAY TRAFFIC CONTROLLING
APPARATUS

Charles H. Lay, Swissvale, Pa., assignor to The
Union Switch & Signal Company, Swissvale,
Pa., a corporation of Pennsylvania

Application December 29, 1937, Serial No. 182,278

5 Claims. (Cl. 246—135)

My invention relates to railway traffic controlling apparatus, and particularly to apparatus of the type involving power operated track switches controlled by a manually operable means, such as 5 by levers of an interlocking machine.

A feature of my invention is the provision of novel and improved apparatus for indicating at the manually operable lever of an interlocking machine the position of a power actuated track 10 switch and of the controlling apparatus therefor. A further feature of my invention is the provision of apparatus of the type here involved for controlling the well-known polarized indication 15 relay and the indication lock magnets associated with switch levers of interlocking machines. Other features and advantages of my invention will appear as the specification progresses.

I shall describe two forms of apparatus embodying my invention, and shall then point out the 20 novel features thereof in claims.

In the accompanying drawing, Fig. 1 is a diagrammatic view of apparatus embodying my invention when applied to the control apparatus of an electropneumatic switch and lock movements or mechanism of a single railway switch. Fig. 2 is a diagrammatic view of apparatus embodying my invention applied to the control apparatus of electropneumatic switch and lock movements or mechanisms for crossover switches.

30 In each of the two views, similar reference characters designate similar parts.

Referring to Fig. 1, the reference character SW designates a railway track switch which is actuated by an electropneumatic switch operating mechanism SM. This switch operating mechanism may, for example, be of the type shown and described in the United States Letters Patent No. 1,713,169, granted May 14, 1929, to J. P. Coleman for Railway traffic controlling apparatus. It is sufficient for the present application to say that when the normal control valve magnet NV and the lock control magnet LV of the mechanism SM are energized the mechanism is operated as required to move the track switch to its normal position, that is, the position illustrated in Fig. 1; and when the reverse control valve magnet RV and the lock control valve magnet LV are energized, the mechanism SM is operated as required to move the track switch to its reverse position, that is, to the position opposite that illustrated in Fig. 1.

A controller H1 comprising two movable contact members 11 and 12 is connected with the control valves of the mechanism SM, as indicated 55 by a dash line 13, the arrangement being such

that the contact members 11 and 12 are operated to the right-hand position, as viewed in Fig. 1, closing contacts 11—14 and 12—15 when the control valves of the mechanism SM are actuated as required to move the track switch to its normal position, and the contact members 11 and 12 are operated to the left-hand position, as viewed in Fig. 1, closing contacts 11—16 and 12—17 when the control valves of the mechanism are actuated as required to move the track switch to its 10 reverse position.

A second controller H2 comprising four movable contact members 18, 19, 20 and 21 is connected with the mechanism SM and with the track switch SW by any suitable means indicated by a dash line 22. The parts are so constructed that contact members 18 and 19 are operated to engage contacts 23 and 24, respectively, only when the switch SW is locked in its normal position, and at all other times the contact members 18 and 19 20 make engagement with contacts 25 and 26, respectively. In a similar fashion, the contact members 20 and 21 are operated to engage the contacts 27 and 28, respectively, only when the switch is locked in its reverse position, and at 25 all other times contact members 20 and 21 make engagement with contacts 29 and 30, respectively.

The switch mechanism SM is controlled by a manually operable lever L, such as, for example, a switch lever of an interlocking machine. The lever L comprises a handle 31 and a controller including a plurality of contact members indicated by the reference characters 1 to 8, inclusive. The diagram appearing below the handle 31 indicates the principal positions which may be occupied by the lever L. These positions are: full normal position N, full reverse position R, normal indication position B, reverse indication position D, and two intermediate positions X and Y. The contact members 1 to 8 are actuated by the handle 31 to engage associated stationary contacts to complete different circuit contacts at different positions of the lever. The positions in which the various contact members engage the associated contacts are designated by reference characters 35 which correspond to the diagram. For example, the contact member 1 is designated by the reference character RD, which means that the contact member 1 engages the associated contact to close the circuit when the lever is moved to its reverse 40 indication position, to its reverse position, and to any position between these two.

Associated with the lever L are a normal indication lever lock NL and a reverse indication lever lock RL. The lock NL comprises a segment 32 55

connected with the handle 31 and a magnet 33 having a locking dog 34 controlled thereby. The locking dog 34 cooperates with the segment 32 in the usual manner and prevents, when the lever 5 is moved toward its normal position, movement of the lever past its normal indication position unless magnet 33 is energized. Also, movement of lever L away from the normal position is prevented unless magnet 33 is energized. In like 10 manner, the lock RL comprises a segment 35 connected with the handle 31 and a magnet 36 having a locking dog 37 controlled thereby. The locking dog 37 cooperates with the segment 35, and in the usual manner prevents, when the lever 15 is being moved toward the reverse position, movement past the reverse indication position unless the magnet 36 is energized. Also, magnet 36 must be energized and dog 37 lifted in order for the lever to be moved away from the reverse 20 position. As in usual practice, a latch contact 39 is provided for handle 31, the arrangement being such that contact 39 is biased by its own spring action to an open position and is closed when the latch on handle 31 is actuated in preparation for 25 moving the lever away from either its normal or reverse position.

The indication lock NL and the indication lock 30 RL are in part governed by an indication relay KR, which as here shown is a direct current polarized relay. The relay KR also cooperates with contacts of the lever L in controlling the mechanism SM.

It is believed that the circuits involved in Fig. 1 can best be understood by a description of the 35 operation of the apparatus. At the start, the apparatus is assumed to occupy its normal position, that is, the position illustrated in Fig. 1. In this normal position, the indication relay KR is energized over a normal indication circuit. 40 This normal indication circuit can be traced from the B14 terminal of any convenient source of current, such as a battery not shown, over resistance 40, contact 18-23 of controller H2, indication wire 41, winding of relay KR, indication wire 42, contact 19-24 of controller H2, contact 11-14 of controller H1 and to the terminal C14 of the current source. The current supplied to relay KR by this normal indication 45 circuit is of normal polarity, so that the relay KR is energized to operate its polar contact fingers 43 and 44 to the left-hand position, as viewed in Fig. 1, making contact with normal polar contacts 45 and 46, respectively. Also, under the normal 50 position of the apparatus, the normal valve magnet NV is energized over a circuit extending from terminal B14, the NB contact of contact member 2, resistance 47, control wire 48, winding of valve magnet NV and to the terminal C14.

I shall next assume that the operator desires 55 to reverse the position of the track switch and to that end moves the lever L to its reverse indication position D. When the latch of handle 31 is lifted in preparation of moving the lever away from its normal position, the contact 39 is closed and a circuit is completed for the magnet 33, and current flows from terminal B14 over the usual detector circuit control, contact 39, the NX contact of contact member 5, winding of magnet 60 33, indication wire 42, contact 19-24 of controller H2, contact 11-14 of controller H1 and to the C14 terminal. With magnet 33 thus energized to lift its locking dog 34, the segment 32 is released and in turn the lever L, so that the lever may be moved to its reverse indication 65 position.

sition where its movement is arrested by virtue of the locking dog 37 engaging the usual notch in the segment 35. In this reverse indication position D, the lock valve magnet LV is energized by virtue of a circuit extending from terminal B14 5 over front neutral contact 49 of relay KR, the RD contact of contact member 4, normal polar contact 44-46 of relay KR, control wire 50, winding of lock valve magnet LV and to the terminal C14. The reverse valve magnet RV is also 10 provided with a circuit extending from terminal B14 over the RD contact of contact member 1, resistance 51, control wire 52, winding of valve magnet RV, and to the terminal C14.

When the valve magnets LV and RV are energized 15 the controller H1 is first operated to shift its contact members 11 and 12 to the left-hand position in the manner explained hereinbefore. When the contact members 11 and 12 are thus shifted the normal indication circuit is opened 20 and relay KR is deenergized and released. The circuit for the lock valve magnet LV is now completed over the back contact 53 of relay KR, as will be readily understood by an inspection of Fig. 1. With valve magnets LV and RV energized 25 air pressure is applied to the mechanism for operating the switch. At the start of the operation, the mechanism SM unlocks the track switch, and in so doing the controller H2 is operated to shift the contact members 18 and 19 from 30 engagement with contacts 23 and 24 to engagement with contacts 25 and 26, respectively. When the contact members 18 and 19 are thus shifted, the winding of relay KR is short-circuited by 35 virtue of two connections between the indication wires 41 and 42. One of these connections includes contact 18-25 and contact 21-30 of controller H2, and the other connection includes contact 20-29 and contact 19-26. When the switch is moved and locked in its reverse position, 40 the controller H2 is operated to shift its contact members 20 and 21 in the manner explained hereinbefore. With both controllers H1 and H2 thus operated, a reverse indication circuit for relay KR is completed, and which circuit extends 45 from terminal B14 over resistance 40, contact 21-28 of controller H2, indication wire 42, winding of relay KR, indication wire 41, contact 20-27 of controller H2, contact 12-17 of controller H1 and terminal C14. The relay KR is now energized 50 with current of reverse polarity and actuates its polar contact fingers 43 and 44 to make engagement respectively with reverse polar contacts 54 and 55. It follows that to energize relay KR with current of reverse polarity agreement as 55 to position is required between the track switch and the control valves of the mechanism SM.

When the relay KR is picked up to open its back contact 53, the lock valve magnet LV is deenergized and the mechanism SM is cut off from 60 the air pressure. With relay KR energized in its reverse position, the magnet 36 is provided with a circuit. This circuit for magnet 36 can be traced from terminal B14 over front contact 49 of relay KR, the RD contact of contact member 65 4, reverse polar contact 44-55 of relay KR, the ND position of contact member 8, winding of magnet 36, indication wire 41, contact 20-27 of controller H2, contact 12-17 of controller H1 and terminal C14. With magnet 36 thus energized, 70 its locking dog 37 is lifted to permit the movement of the lever L to its full reverse position R, where the contact ND of contact member 8 is opened and magnet 36 is deenergized. It is to be seen, therefore, that to energize the lock 75

magnet 36, agreement as to position is required between the lever L, the indication relay KR, the switch SW and the control valves of the mechanism SM.

In case the control valves of mechanism SM should operate to their reverse positions to reverse controller H1, but due to some faulty connection between the mechanism SM and the track switch, or other failure, the controller H2 remains in its normal position, the indication relay KR is short-circuited by virtue of a path extending from indication wire 41 over contact 18-23 of controller H2, contact 11-16 of controller H1, contact 19-24 of controller H2 and to the other indication wire 42. Also under such circumstances, the circuit for the magnet 36 is connected with the terminal B14 adjacent the switch location over the contact 18-23 of controller H2, and thus false energization of magnet 36 is avoided. Again, in the event the mechanism SM and switch SW are operated to their reverse positions, but the polar contact fingers of relay KR fail for some reason to respond to the reverse energization of relay KR, the circuit for the lock magnet 36 remains deenergized since it is held open at the reverse polar contact 44-55 of relay KR, and with magnet 36 deenergized the lever L is locked at its reverse indication position to check the failure of the indication relay KR. In Fig. 1, a lever indicating lamp 56 is provided and is illuminated over a simple circuit including back contact 57 of relay KR.

I shall next assume that the operator desires to restore the switch to its normal position and to that end moves the lever L to its normal indication position B. The lifting of the latch of handle 31 in preparation for movement of the lever away from its reverse position closes contact 39 and completes a circuit for magnet 36. This circuit involves terminal B14, the usual detector circuit control, contact 39, the RY contact member 6, winding of magnet 36, indication wire 41, contact 20-27 of controller H2, contact 12-17 of controller H1 and terminal C14. With magnet 36 thus energized, its locking dog 37 is lifted to permit the movement of segment 35 and in turn movement of lever L away from its reverse position. At the normal indication position B of lever L, its movement is arrested by locking dog 34 engaging the usual notch in the segment 32. At the normal indication position of lever L, the previously traced circuit for normal valve magnet NV is formed to energize that valve magnet. This time, the lock valve magnet LV is energized by current supplied from terminal B14 over front contact 49 of relay KR, the NB contact of contact member 3, reverse polar contact 43-54 of relay KR, control wire 50, winding of valve magnet LV and terminal C14.

With both valve magnets NV and LV energized, the mechanism SM is operated to move the switch to its normal position. When the control valve magnets NV and LV are actuated, the controller H1 is operated to shift its contact members 11 and 12 into engagement with the respective contacts 14 and 15 so that the indication relay KR is deenergized, the circuit for magnet LV being now completed at back contact 53 in the manner described hereinbefore. When the mechanism SM is operated to unlock the switch, the controller H2 is moved to shift its contact members 20 and 21 to the position illustrated in Fig. 1, and when the switch is moved and locked in its normal position the controller H2 is operated to shift its contact members 18 and 19 to the position illus-

trated in Fig. 1. Under this condition of the controllers H1 and H2, the previously traced normal indication circuit for relay KR is completed and that relay is energized with current of normal polarity. When relay KR is energized and operated to its normal position, the magnet 33 of the normal lock NL is energized, the circuit extending from terminal B14 over front contact 49 of relay KR, the NB contact of contact member 3, normal polar contact 43-45 of relay KR, the RB contact of contact member 7, winding of magnet 33, indication wire 42, contact 19-24 of controller H2, contact 11-14 of controller H1 and terminal C14. With magnet 33 thus energized to lift its locking dog 34, the segment 32 and in turn the lever L is released to permit the lever L to be moved to its full normal position, where the contact RB of contact member 7 is opened and magnet 33 is deenergized.

Should the switch and controller H2 fail to move to the normal position in response to operation of the mechanism SM, the relay KR is short-circuited by a path extending from the indication wire 41 over contact 20-27 of controller H2, contact 12-15 of controller H1, contact 21-28 of controller H2 and to the other indication wire 42. Also, the circuit for the magnet 33 is connected to the B14 terminal of the current source at the switch location over the contact 21-28 of controller H2. It is to be noted that magnet 33 can be energized when and only when there is agreement as to position between the lever L, the indication relay KR, the switch SW and the control valves of the mechanism SM.

In Fig. 2, the switches SW1 and SW2 of a crossover are operated by means of the respective electro-pneumatic switch mechanisms SM1 and SM2. A controller H5 is operated from the control valves of the mechanism SM1, and a controller H6 is operated from the control valves of the mechanism SM2, in the same manner that controller H1 of Fig. 1 is operated from the control valves of the mechanism SM. Controllers H3 and H4 of Fig. 2 correspond to the controller H2 of Fig. 1 and are operated by the mechanisms SM1 and SM2, respectively. Looking at controller H3, the movable contact members 58 and 59 make engagement with the respective contacts 60 and 61 only when the switch SW1 is locked in its normal position, and at all other times they engage the two contacts 62 and 63, respectively. Contact members 64 and 65 make engagement with contacts 66 and 67 only when the switch SW1 is locked in the reverse position, and at all other times they engage the contacts 68 and 69, respectively. In controller H4, the contact members 70 and 71 engage the respective contacts 72 and 73 only when the switch SW2 is locked in its normal position, and the contact members 74 and 75 engage the respective contacts 76 and 77 only when the switch SW2 is locked in the reverse position, and at all other times the contact members 70, 71, 74 and 75 engage the contacts 78, 79, 80 and 81, respectively.

The lever L, normal lock NL, reverse lock RL and indication relay KR of Fig. 2 are the same as in Fig. 1. The mechanisms SM1 and SM2 are controlled by the lever L over control circuits, the same as in Fig. 1 except for the fact that the respective valve magnets of mechanisms SM1 and SM2 are connected in series and the resistances 47 and 51 are omitted, as will be readily understood by an inspection of Fig. 2.

With the crossover in its normal position as illustrated in Fig. 2, a normal indication circuit is

formed for the relay KR, which circuit checks the positions of the two switches of the crossover and the positions of the control valves of the two respective switch mechanisms. This normal indication circuit involves the following elements: terminal B14, resistance 40, contact 70—72 of controller H4, contact 58—60 of controller H3, indication wire 41, winding of relay KR, indication wire 42, contact 59—61 of controller H3, contact 84—85 of controller H5, contact 71—73 of controller H4, contact 86—87 of controller H6 and terminal C14.

To reverse the crossover, the lever L is moved to its reverse indication position D where control circuits are completed for the respective lock valve magnets LV1 and LV2 of the mechanisms SM1 and SM2 and for the reverse valve magnets RV1 and RV2 of these two mechanisms, these control circuits being substantially the same as described in Fig. 1 and need not be repeated. When the latch is lifted the magnet 33 is energized in a manner similar to that in Fig. 1 and thereby permits the lever to be moved away from the normal position.

When the two switches of the crossover are locked in their reverse positions, a reverse indication circuit is formed for the relay KR, which circuit involves the following elements: terminal B14, resistance 40, contact 75—77 of controller H4, contact 65—67 of controller H3, indication wire 42, winding of relay KR, indication wire 41, contact 64—66, contact 88—89, contact 74—76, contact 82—83 and the terminal C14. With relay KR energized with current of reverse polarity, a circuit is formed for the magnet 36 of the reverse lock RL, the circuit extending from terminal B14 over front contact 49 of relay KR, the RD contact of contact member 4, reverse polar contact 44—55, the ND contact of contact member 8, winding of magnet 36, indication wire 41, and thence to the terminal C14 over the same path traced for the reverse indication circuit of relay R.

To operate the crossover to its normal position, the lever L is moved to its normal indication position B where control circuits are formed for the lock valve magnets LV1 and LV2, and the normal valve magnets NV1 and NV2 of the mechanisms SM1 and SM2, these control circuits being substantially the same as in Fig. 1. When the latch is lifted the magnet 36 is energized in a manner similar to that in Fig. 1 to permit movement of the lever from the reverse position.

With the two switches of the crossover locked in their normal positions, the previously traced normal indication circuit for relay KR is completed and that relay is energized with current of normal polarity. A circuit for the magnet 33 of lock NL is now formed which involves the elements B14, front contact 49, the NB contact of contact member 3, normal polar contact 43—45, the contact RB of contact member 7, winding of magnet 33, indication wire 42 and thence to the terminal C14 over the same path included in the normal indication circuit for relay KR.

It is to be pointed out that when the crossover is moved to the reverse position the circuit for the magnet 33 of the reverse lock is completed when and only when there is agreement as to position between the lever L, relay KR, switch SW1, control valves of mechanism SM1, switch SW2, and control valves of mechanism SM2. Also, when the crossover is moved to its normal position, the circuit for the magnet 33 of the normal lock NL is completed when and only when there is agreement as to position between the

lever L, relay KR, switch SW1, control valves of mechanism SM1, switch SW2 and control valves of mechanism SM2.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a railway switch connected with a switch mechanism for moving the switch to its normal and reverse positions and said mechanism having a control element for reversibly controlling said mechanism, a first controller connected with the switch mechanism for closing normal and reverse contacts in response to corresponding positions of the switch, a second controller connected with said control element for closing normal and reverse contacts in response to corresponding positions of the control element, a switch lever having a normal and a reverse indication position to control said control element for operating said mechanism to its respective normal and reverse positions, a lever controller connected with said switch lever for closing normal indication and reverse indication contacts, a polarized relay, a normal and a reverse lever lock magnet for governing said switch lever, a normal indication circuit for said relay including a normal contact of each of said first and second controllers, a reverse indication circuit for said relay including a reverse contact of each of said first and second controllers, a circuit for said normal lock magnet including a normal indication contact of said lever controller and a normal polar contact of said relay as well as a normal contact of each of said first and second controllers, and a circuit for said reverse lock magnet including a reverse indication contact of said lever controller and a reverse polar contact of said relay as well as a reverse contact of each of said first and second controllers.

2. In combination, a railway switch connected with a switch mechanism for moving the switch to its normal and reverse positions, a controller connected with the switch mechanism for closing normal and reverse contacts in response to corresponding positions of the switch, a switch lever of an interlocking machine including a controller having normal indication contacts and reverse indication contacts for governing said mechanism to its respective normal and reverse positions, a polarized indication relay, a normal and a reverse lever lock magnet for governing the movement of said lever, an indication circuit including normal and reverse contacts of said switch mechanism controller for reversibly energizing said relay according to the position of the switch; a circuit of said normal lock magnet including a normal indication contact of said lever controller, a normal polar contact of said relay and a normal contact of said switch mechanism controller; and a circuit of said reverse lock magnet including a reverse indication contact of said lever controller, a reverse polar contact of said relay and a reverse contact of said switch mechanism controller.

3. In combination, a railway switch connected with a switch mechanism for moving the switch to its normal and reverse positions, a controller connected with the switch mechanism for closing normal and reverse contacts in response to corresponding positions of the switch, a switch

lever of an interlocking machine including a controller having normal indication contacts and reverse indication contacts for governing said mechanism to its respective normal and reverse positions, a polarized indication relay, a normal and a reverse lever lock magnet for governing the movement of said lever, an indication circuit including normal and reverse contacts of said switch mechanism controller for reversibly energizing said relay according to the position of the switch; a circuit for said normal lock magnet including a normal indication contact of said lever controller, a normal polar and a front neutral contact of said relay and a normal contact of said switch mechanism controller; and a circuit for said reverse lock magnet including a reverse indication contact of said lever controller, a reverse polar and front neutral contact of said relay and a reverse contact of said switch mechanism controller.

4. In combination, a railway switch connected with a switch mechanism for moving the switch to its normal and reverse positions, a first controller connected with the switch mechanism for closing normal and reverse contacts in response to corresponding positions of the switch, a second controller connected with said mechanism for closing normal and reverse contacts in response to corresponding positions of the mechanism, a switch lever of an interlocking machine including a controller having normal and reverse indication contacts, control means including normal and reverse indication contacts of said lever controller for governing said mechanism to its respective normal and reverse positions, a polarized relay, a normal and a reverse lever lock magnet for governing said lever, a normal indication circuit for said relay including a first indication wire connected with the positive terminal of a current source over a normal contact of said first controller and a second indication wire connected with the negative terminal of the current source over a normal contact of said first and second controllers in series, a reverse indi-

cation circuit of said relay including said second wire connected with said positive terminal over a reverse contact of said first controller and said first wire connected with the negative terminal over a reverse contact of said first and second controllers in series; a circuit for said normal lock magnet extending from the positive terminal of the source over a normal indication contact of said lever controller, a normal polar contact of said relay, winding of the magnet and to said second wire; and a circuit for said reverse lock magnet extending from the positive terminal of the source over a reverse indication contact of said lever controller, a reverse polar contact of said relay, winding of the magnet and to said first wire.

5. In combination, a railway switch connected with a switch mechanism for moving the switch to its normal and reverse positions and said mechanism having a control element for reversibly controlling said mechanism, a first controller connected with the switch mechanism for closing normal and reverse contacts in response to corresponding positions of the switch, a second controller connected with said control element for closing normal and reverse contacts in response to corresponding positions of the control element, a switch lever of an interlocking machine having a controller including normal indication and reverse indication contacts, a normal and a reverse lever lock magnet for governing the movement of said lever, circuit means including normal and reverse contacts of the lever controller to control the control element for reversibly operating said switch mechanism, a circuit for said normal lock magnet including a normal indication contact of said lever controller and a normal contact of each of said first and second controllers, and a circuit for the reverse lock magnet including a reverse indication contact of said lever controller and a reverse contact of each of said first and second controllers.

CHARLES H. LAY.
